TOY HELICOPTER

Roy R. Carrington, Fulton, Mo.

Application September 17, 1946, Serial No. 697,491

6 Claims. (Cl. 46—75)

1

The invention relates generally to flying toys and more particularly to a toy helicopter.

The general object of the invention is to provide a novel toy helicopter in a form which may be inexpensively constructed and which is capable of effecting flight for a sustained period of time.

Another object is to provide a toy helicopter having a bladed rotor adapted to assume automatically a pitch suitable for ascent when the rotor is driven, and a different pitch for descent.

A further object is to provide a toy helicopter having a bladed rotor adapted to assume a pitch suitable for ascent when the rotor is driven, and another pitch suitable to effect autorotation when the device is descending.

Still another object is to provide a toy helicopter having a pair of bladed rotors driven in opposite directions to nullify the torque effect of a single rotor and with the blades of the upper rotor so supported as to provide for automatic adjustment thereof to provide pitches suitable for both for ascent and descent.

Other objects and advantages will become apparent from the following description taken in connection with the accompanying drawings, in which:

Figure 1 is a side elevational view on a reduced scale of a toy helicopter embodying the features of the invention.

Fig. 2 is a view similar to Fig. 1 but taken in a plane at right angles to that of Fig. 1.

Fig. 3 is a plan view of the toy shown in Fig. 1.

Fig. 4 is a vertical sectional view taken on the line 4—4 of Fig. 1.

Fig. 5 is a fragmentary sectional view taken on the line 5—5 of Fig. 1.

Fig. 6 is a side elevational view similar to Fig. 1 showing a modified form of construction.

Fig. 7 is a plan view of the device shown in Fig. 6.

Fig. 8 is a fragmentary sectional view taken on the line 8—8 of Fig. 6.

Fig. 9 is a plan view of another modified form of helicopter.

Fig. 10 is a side elevational view similar to Fig. 1 but showing the modified form of Fig. 9.

Fig. 11 is a side elevational view in a plane at right angles to the plane of Fig. 10 and showing the device when the power of the drive motor has been expended.

Fig. 12 is a view similar to Fig. 11 but showing the position of the parts thereof when the drive motor is ready for operation.

Toy helicopters have heretofore been con-

structed in a manner to provide oppositely rotating rotors driven by a motor such as a rubber band motor, but very little if any attention has been given to the question of operation of the device after the drive motor has expended its power. In many prior structures, the device merely plunged to earth without any attempt being made to control the descent. In other prior structures, a parachute has been attached to the device to control the descent, but in none of them has an attempt been made to utilize the rotors to control the descent.

With the present invention, the helicopter is so constructed that one of the rotors controls the descent in such a manner as to cause the device to descend in an upright position at a relatively slow rate so that the descent is just as much a feature of the device as is the ascent. To this end, one of the rotors of the device is provided with a pitch suitable to cause autorotation thereof which results in a smooth relatively slow downward movement of the device. Such pitch of the rotor, however, is unsuited to effect a rapid climb of the device when being driven by the drive motor. The device, therefore, provides means for automatically increasing the pitch of the rotor as an incident to its being driven by the drive motor. When the drive motor has expended its power and ascent is completed, the rotor returns to its normal position with a pitch suitable for the above mentioned autorotation. Such relatively slow descent not only increases the time and manner of flight but also avoids damage to the device through impact with the earth when descending at a faster rate. The structure of the device, therefore, need not be as rigid as heretofore necessary and consequently less weight is involved and the device can be caused to ascend to a greater height for a given motor power.

In all of the embodiments shown herein, I provide a body structure carrying a rotor at its lower end with a second rotor of much larger diameter located adjacent the upper end. The lower rotor is rotatable relative to the body while the upper rotor is fixed to the body for rotation therewith. Mounted within the body is a motor preferably of the rubber band type connected to rotate the lower rotor in one direction and the body with the upper rotor in the opposite direction. The principal feature of the invention lies in the manner in which the blades of the upper rotor are attached or connected to the body so that when the drive motor has expended its power, such blades will maintain a pitch of ap-

proximately 2° to the horizontal which is suitable for autorotation. However, when the rubber band motor is wound up and the opposite rotation of the rotors takes place, as in ascent, the blades of the upper rotor automatically assume a position of increased pitch suitable to effectively carry the craft upward.

In the embodiment shown in Figs. 1 to 5 of the drawings, the body structure comprises in this instance an elongated tube 20. Such tube may be made of any suitable material of light weight such as plastic material, paper, or thin metal. Located at one end of the tube 20, which end constitutes the lower end in ascent, is a lower rotor 21. The rotor 21 comprises a pair of oppositely extending blades of relatively steep pitch, the blades being integral with each other and provided with a hub or central portion in the form of a metallic clip 22 wrapped about the rotor. To rotatably support the rotor, a shaft in the form of a wire 23 extends through the clip 22 and is hooked over the lower edge thereof, as at 24, so that the shaft 23 is rigid with the rotor. The shaft 23 extends upwardly into the tube 20 and is provided with a thrust bearing in the form of metallic washers 25 interposed between the clip 22 and a cap 26 frictionally retained on the lower end of the tube 20.

The drive motor in the present instance is a rubber band 30 comprising a plurality of strands extending upwardly within the tube 20. The lower end of the rubber band 30 is connected to the shaft 23, a hook 31 being provided on the upper end of the shaft to detachably engage the strands of the rubber band. The upper end of the rubber band is adapted to be secured to the tube 20 preferably at the upper end thereof. To this end I provide a plug 32 mounted in the upper end of the tube and frictionally retained therein. The plug 32 is provided with a pair of ears or drive lugs 33 interfitting with notches formed in the upper end edge of the tube. Extending centrally through the plug 32 is a wire 34 having a hook 35 at its lower end over which the upper end of the strands 30 of the rubber band motor are engaged. Should any of the strands of the motor break, the cap 26 at the lower end of the tube and the plug 32 at the upper end thereof may be readily removed and the ends of new strands of rubber engaged over the hooks 31 and 35.

A second rotor is provided, which preferably is of substantially larger diameter than the rotor 21 and is mounted adjacent the upper end of the tube 20. The upper rotor is rigidly secured to the tube 20 so that when the rubber band is wound by turning the lower rotor 21 relative to the body 20, the upper rotor and body will rotate in one direction while the lower rotor 21 will rotate in the opposite direction. The upper rotor in the present instance comprises a pair of oppositely extending blades 40 connected by an integral intermediate portion 41 centrally apertured to fit over the tube 20. The intermediate portion 41 is rigidly secured to the tube 20 by means of a clip comprising a band 42 wrapped about the tube 20 and having a pair of ears 43 extending through slots in the intermediate portion 41 and bent against the upper surface thereof. The upper rotor thus is secured to the tube 20 for rotation therewith.

The principal feature of the invention lies in the fact that the upper rotor is so mounted that the blades 40 thereof will have an increased

pitch when being driven so as to produce a rapid ascent. To this end the intermediate portion 41 of the upper rotor is generally U-shaped with the middle portion of the U rigidly secured to the tube 20 by the clip 42. The two arms of the U extend upwardly along side the tube 20 to merge into the blades 40. When the upper rotor is being driven by the rubber band motor 30, there is a centrifugal force resulting from such rotation which tends to move the blades 40 away from the tube 20 and thus spread the arms of the intermediate or U-shaped portion 41. Likewise the resistance of the air to the rotation of the blades produces a torque which has a similar spreading effect on the arms of the U-shaped portion. Such spreading of the arms of the U-shaped portion, as is obvious from Fig. 5, will cause the blades 40 to tilt at a greater pitch angle than they normally assume when stationary or when rotating at a slow speed. Thus I may provide a pitch angle of approximately 2° for the blades when in their normal or idling position, which angle is suitable for autorotation and when such blades are driven at a speed sufficient to cause ascent, they may assume a position of substantially increased pitch as indicated by the dotted lines in Fig. 5. Thus, while the device is being driven upwardly by the rubber band motor, the blades of the upper rotor 30 have a pitch suitable for such ascent. When the rubber band motor has expended its power, the blades reassume their normal pitch which is suitable for autorotation. The descent of the device thus causes the upper blades to rotate, materially slowing the speed of descent and maintaining the device in an upright position during such descent. To increase the flexibility of the arms of the U-shaped portion 41 and thus increase the angle to which such arms are bent by the centrifugal force and torque, the arms may be structurally weakened to a slight extent at their point of connection with the blades 40. In the present instance, I have increased the flexibility by providing apertures 44 adjacent the point where the arms of the U-shaped portion 41 merge into the blades 40.

In the modified form shown in Figs. 6, 7 and 8 I show a toy helicopter in which the blades of the upper rotor are similarly supported to alter the pitch thereof. The structure of the device shown in these figures, however, differs in a number of respects from that shown in Fig. 1. Thus as shown in Fig. 6 the body structure comprises a pair of elongated side bars 50 arranged in laterally spaced relation to each other and integrally connected at their lower ends by a curved portion 51. The upper ends of the side bars 50 are interconnected by a flattened portion 52. Intermediate the ends of the body structure or frame 50 is a reenforcing strip 53 extending from one side bar to the other. The lower rotor here indicated at 54 comprises a pair of outwardly extending blades mounted on a hub 55 secured to a shaft in the form of a wire 56 extending through the curved portion 51. A thrust washer 57 may be interposed between the hub 55 and the curved portion 51 to eliminate friction. The upper end of the shaft 56 is provided with a hook 58 adapted to receive the strands of a rubber band motor 60. The rubber band motor 60 extends upwardly between the side bars 50 and at its upper end it engages a hook 61 rigidly secured to the flattened portion 52 at the upper end of the side bars. The rubber band motor 60 when wound thus will cause the lower rotor 54 to rotate in one direction

while the body or frame structure rotates in the opposite direction.

The upper rotor in the present instance comprises a pair of oppositely extending blades 62 having their inner ends extending adjacent but on opposite sides of the frame structure and spaced above the upper end 52 thereof. Connecting the blades with the frame structure is a U-shaped member 63 having a flattened intermediate portion rigidly secured to the flattened end portion 52 of the frame structure. The two arms of the U extend upwardly therefrom and are secured at their upper or free ends to the inner ends of the blades 62.

The U-shaped member 63 in this instance has a similar action to the intermediate portion 41 of the previously described form. Thus it has sufficient flexibility to permit the centrifugal force and torque due to air resistance arising from rotation of the upper blades when driven by the rubber band motor 60, to cause the arms of the U to flare outwardly, as indicated in Fig. 8, and thus increase the angle of pitch of the blades 62. As in the case of the previously described form, the blades 62 of the present form will assume an angle of pitch sufficient to cause rapid ascent when being driven by the rubber band motor 60 but when the latter has expended its power, the blade 62 will assume a lesser angle of pitch suitable for autorotation during descent.

In the modified form shown in Figs. 9 to 12, inclusive, I have provided a device having a body or frame structure generally similar to that shown in Fig. 6. Thus I provide a pair of laterally spaced elongated side bars 70 having curved interconnecting portions 71 at both ends. At the lower end of the frame I provide a rotor comprising blades 72 connected to a shaft 73 extending through the lower curved portion 71 with a thrust washer 74 interposed therebetween. The upper end of the shaft 73 is formed into a hook 75 to receive the lower end of a rubber band motor 76. The upper end of the rubber band motor is engaged over a hook 77 rigidly secured to the upper curved portion 71 so that when the rubber band motor is wound up, the frame structure will be rotated in one direction while the lower rotor blades 72 will be driven in the opposite direction.

The upper rotor in this instance comprises a pair of oppositely extending blades 80 which are directly connected to the respective side bars 70, and the side bars are made of flexible material adapted to be bowed by increased tension of the rubber band motor 76 when the latter is wound to increase the pitch of the blades 80 when the rubber band motor is driving the device. Thus as illustrated in Fig. 11, the rubber band motor 76 when unwound will exert only a slight tension on the two ends of the frame structure causing the side bars 70 to assume a predetermined position. With such position of the side bars, the blades 80 are secured thereto in a manner to provide the desired pitch for autorotation. However, when the rubber band motor 76 is wound, a greatly increased longitudinal tension is exerted on the side bars 70 causing them to bow outwardly, as shown in Fig. 12. Such outward bowing causes the blades 80 to assume an increased pitch angle which is so calculated as to be the desired pitch for rapid ascent. In order to render the outward bowing of the side bars 70 sufficient to attain the desired pitch angle of the blades 80, I may confine the bowing of the side bars to a predetermined portion of the length 75

thereof. Thus I may connect the two side bars at a point between the upper and lower rotors by a reenforcing strip 81, which in the present instance is of curved form as shown in Fig. 9. The reenforcing strip 81 holds the side bars 70 to a substantially constant spacing so that bowing of the side bars due to the tension of the rubber band motor when wound will occur in that portion lying between the reenforcing member 81 and the upper end thereof. Such bowing is of a sharper curvature than if the bowing were permitted throughout the entire length of the side bars and consequently a greater angle of pitch for the blades 80 may thereby be attained.

In all of the forms shown herein the rubber band motor may be wound by grasping the body structure in one hand and rotating the lower rotor in the correct direction. When the rubber band motor has been wound to the desired extent, the lower rotor is held against rotation until the upper rotor is turning at the desired speed. The lower rotor is then released and rotates in the opposite direction to the upper rotor, the entire device being lifted rapidly. The upper rotor in all of these forms is of sufficient size so that the rubber band motor cannot expend its power in a very short time. Consequently the power drive thereof will occur for a substantial period of time, causing the device to ascend to quite a height. When the power is expended, the blades of the upper rotor in each of the forms will reassume their normal position at a pitch angle suitable to produce autorotation thereof and the device descends smoothly in an upright position and at a relatively slow speed.

I claim:

1. A toy helicopter comprising a body structure, a lower bladed rotor rotatably mounted on the lower end of said structure, a drive motor mounted in said body structure and connected to said rotor and said body structure to effect opposite rotation thereof, a flexible U-shaped member having a central portion rigidly secured to the upper portion of said body structure and flexible arms extending upwardly, and a pair of transversely tiltable elongated blades fixed at their inner ends to the upper ends of said arms, the longitudinal axes of said blades extending substantially perpendicularly with respect to the plane of movement of said flexible arms whereby said arms tend by centrifugal force to bend outwardly under the driving force of said motor to increase the pitch of said blades.

2. A toy helicopter comprising a tube, a lower bladed rotor rotatably mounted on the lower end of said tube, drive means mounted in said tube and connected to said lower rotor and said tube to effect opposite rotation thereof, and an upper rotor comprising a pair of elongated transversely tiltable blades fixed at their inner ends to a bowed intermediate portion rigidly secured to said tube and adapted to flex by centrifugal force when driven by said drive means, the longitudinal axis of said blades extending generally perpendicularly with respect to the plane of flexing movement of said bowed portion whereby the pitch of the blades is increased upon said flexing movement.

3. A toy helicopter comprising a tube, a lower bladed rotor rotatably mounted on the lower end of said tube, drive means mounted in said tube and connected to said lower rotor and said tube to effect opposite rotation thereof, an upper rotor comprising a pair of elongated trans-

versely tiltable blades fixedly connected by a downwardly bowed intermediate portion centrally apertured to fit over said tube, and means for rigidly securing said portion to said tube, said portion being so shaped adjacent said blades as to render it flexible and the longitudinal axes of said blades extending substantially perpendicularly with respect to the plane of flexing movement of said bowed portion whereby centrifugal force created by rotation by 5 said drive means will increase the pitch of the blades.

4. A toy helicopter comprising a tube, a cap frictionally secured on the lower end of said tube, a lower rotor having blades of fixed pitch rotatably carried by said cap, a plug frictionally engaged in the upper end of said tube and rigid therewith, a rubber band motor within said tube connected at one end to said lower rotor and at its other end to said plug, and an upper rotor comprising a pair of elongated transversely tiltable blades fixedly mounted at their inner ends on a bowed connecting portion rigidly secured to said tube, said portion normally holding said blades at a pitch suitable for autorotation on descent and adapted to flex by centrifugal force when driven by said motor, and the longitudinal axes of said blades extending substantially perpendicularly with respect to the plane of flexing movement of said portion whereby the pitch of said blades is increased upon said flexing movement.

5. A toy helicopter comprising a frame comprising a pair of laterally spaced elongated side bars connected at their ends, a bladed rotor rotatably mounted in the lower end of said frame, a rubber band motor extending within said frame and connected at one end to said rotor and at its other end to the other end of said frame, a second rotor comprising a pair of elongated transversely tiltable blades, and a flex-

10

15

ible U-shaped member having its central portion secured to said other end of the frame and its arms extending upwardly therefrom and secured to said blades, the arms of said member being adapted to flex outwardly under centrifugal force created by the driving force of said motor and the longitudinal axes of said blades extending substantially perpendicularly with respect to the plane of flexing movement of said arms whereby the pitch of said blades is increased upon said flexing movement.

6. A toy helicopter comprising a frame comprising a pair of laterally spaced elongated side bars bent at their ends to form interconnecting portions, a bladed rotor rotatably mounted in the lower interconnecting portion, a rubber band motor connected at one end to said rotor and at its other end to the other interconnecting portion, a flexible U-shaped member having its central portion rigidly secured to said other interconnecting portion with the arms of the U extending upwardly beyond said frame and longitudinally therewith, and a pair of elongated blades secured to the free ends of said arms, said blades having their longitudinal axes extending angularly with respect to said arms and said arms being adapted to flex outwardly by centrifugal force to increase the pitch of said blades as an incident to the operation of said motor.
